UNITED STATES PATENT OFFICE.

HENRY FULLER HOBDEN, OF LONGLANDS, BENFLEET, ENGLAND, ASSIGNOR TO
RADIAN COLOUR COMPANY LIMITED, OF LONDON, ENGLAND.

GAME APPARATUS.

1,115,938.

Specification of Letters Patent.

Patented Nov. 3, 1914.

Application filed July 18, 1912. Serial No. 710,148.

To all whom it may concern:

Be it known that I, HENRY FULLER HOBDEN, subject of the King of England, residing at Longlands, Benfleet, Essex, England, have 5 invented a certain new and Improved Game Apparatus, of which the following is a specification.

This invention relates to a new or improved game apparatus requiring skill for 10 the successful manipulation.

The invention consists broadly of providing a ring of metal, wood or any other suitable material, which ring has indications such as numbers denoting values of points 15 to score, printed or otherwise produced thereon. This ring is suspended by a number of cords, wire or the like from a central cap or other equivalent device which cap is mounted when the game is to be played at 20 the top of a suitable support such for instance as a vertical rod screwed or otherwise suitably attached to a stem. The ring is so suspended that the vertical support comes on the inside thereof, the ring being enabled 25 to be rotated and to oscillate from side to side or around the vertical support when set in motion, suitable flanges or the like may be provided on the inner and outer sides of the ring, in order to prevent or to render it 30 difficult for the counters or other devices which are used by the players to leave the surface of the ring.

In playing the game, each player is provided with one or more disks of different 35 colors or suitable markings so as to distinguish those belonging to different players.

The ring is set in rotation and each player endeavors to throw his counters or the like upon the rotating ring in such a way 40 that they come upon the divisions or spaces marked thereon bearing the highest numbers indicated in the points to be scored. The player who thus obtains the largest aggregate of points is the winner. And in 45 order that my said invention may be better understood I will now proceed to describe the same with reference to the drawing accompanying this specification in which:—

Figure 1 is a perspective of the game set 50 up and as it would appear when in play. Fig. 2 shows one form of the ring portion, detached, illustrating the method of hinging same so that it may be folded up into a small compass. Fig. 3 is a sectional view

of the cap; Fig. 4 is a sectional view showing a modified construction of the cap and the manner of attaching wires thereto; Fig. 5 is a plan view of a cap of further modified construction; and Fig. 6 is a sectional view thereof.

The same letters of reference are employed to denote the same parts in all the views.

a shows the base plate or stand which is provided with a central column *b* which is 65 preferably attached to the base *a* so that it can be easily removed for packing. For instance it may be inserted into a socket in the base *a* screwed thereto, or attached in any other suitable way. The column *b* is provided at the top with a spike or point *c*.

d is a cap of metal or other suitable material conical in shape. This cap has a number of strings or wires *e* attached thereto such strings being provided with knots or 75 the like at the end and passing through suitable perforations around the edge of the cap *d*. The strings *e* are attached at the other ends to the edges of the ring *f*. This ring is provided with an inner wall *g* and an 80 outer wall *h*, and is so suspended that it hangs in a horizontal position when at rest.

In the form of the device shown at Fig. 2 the ring is formed of two semi-circular flat pieces of metal, wood, cardboard and the 85 like hinged together by flexible or other hinges at *k* in such a way that when folded out flat a complete ring is formed while when folded together the device takes up a comparatively small space and can be 90 packed with the column *b* and the stand *a* in a box of small dimensions. The surface of the ring *f* is divided into a number of spaces which may be of different colors and carry 95 suitable indicating numerals to denote the number of points to be scored.

Fig. 3 illustrates in detail one method of constructing and mounting the cap. In this figure the cap is provided with a milled head *m* which enables it to be easily twisted 100 so as to set the ring in rotation. In this figure also the strings *e* are passed through the holes *h* and knotted on the inside.

Fig. 4 shows another form of cap *d'* in which an inner upturned portion *p* is provided, suitable perforations being formed through which the strings *e'* are passed in the manner shown at Fig. 5.

Fig. 6 shows another form of the cap d^2 with the channel g formed on the outside, the strings e^2 being preferably passed through holes and arranged in the same 5 manner as illustrated at Fig. 5.

It will be understood that the device may be used in any desired way as a game of skill and that considerable dexterity is required in throwing the counters n or the like 10 upon the ring especially when this latter is rotating and oscillating rapidly. Any suitable set of rules may be drawn up for use in connection with the game.

It will also be understood that the construction given above is merely a representative one as the method of making the device 15 may be varied largely to suit requirements.

Any method of suspending the ring from above its center of gravity may be provided, 20 and the ring may be made up from separate pieces or in any suitable manner.

In general the construction and method of 25 playing may be varied very largely without departing from the principle of the invention.

What I claim as my invention and desire to secure by Letters Patent of the United 30 States of America is:—

1. A game apparatus comprising a support, a ring, means for rotatably and oscillatingly suspending the ring from the sup-

port, and counters adapted to be deposited on the ring.

2. A game apparatus comprising a support, a ring having a flat surface, means for 35 oscillatingly and rotatably suspending the ring from the support and members adapted to be deposited on the ring.

3. In a game apparatus, a support, a ring having a divided surface with indicia there- 40 on, means for oscillatingly and rotatably mounting the ring, and members adapted to be deposited on the ring.

4. In a game apparatus, a support, a ring having a divided surface with indicia there- 45 on, a cap oscillatingly and rotatably mounted on the support, and means connecting the cap and ring whereby the said ring is supported.

5. In a game apparatus, a base or support, 50 a conical shaped cap having a hollow portion resting on the support, a ring containing indicia, means whereby the ring is suspended from the cap, and counters adapted to be deposited on the ring. 55

In testimony whereof I affix my signature in presence of two witnesses.

HENRY FULLER HOBDEN.
